Attorney, Agent, or Firm—Melvin I. Stoltz

CLAIM

The ornamental design for a wet/dry rechargeable shaver, as shown and described.

DESCRIPTION

FIG. 1 is a perspective view of the wet/dry rechargeable shaver showing my new design;

FIG. 2 is a top plan view thereof;

FIG. 3 is a front elevational view thereof;

FIG. 4 is a side elevational view, looking from the right side of FIG. 3, the opposite side being a mirror image thereof;

FIG. 5 is a rear elevational view thereof;

FIG. 6 is a bottom plan view thereof; and,

FIG. 7 is an enlarged view of a portion of the foil as shown in area "7" of FIG. 3.
